UNITED STATES PATENT OFFICE.

ARTHUR J. HASBROUCK, OF GRUNDY CENTER, IOWA.

INITIATION APPARATUS.

Application filed June 23, 1924. Serial No. 721,859.

To all whom it may concern:

Be it known that I, ARTHUR J. HASBROUCK, a citizen of the United States, residing at Grundy Center, in the county of Grundy and State of Iowa, have invented new and useful Improvements in Initiation Apparatus, of which the following is a specification.

The object of my said invention is the provision of an apparatus constructed with a view to startling candidates being initiated in lodges and affording entertainment to those participating in the initiation.

Other objects and practical advantages of the invention will be fully understood from the following description and claims when the same are read in connection with the drawings, forming part of this specification, in which:—

20 Figure 1 is a top plan view illustrating my novel apparatus in set state and as it appears when the cover of the casing is open.

Figure 2 is a longitudinal vertical section showing the apparatus in set state and also 25 showing the cover of the casing in closed position.

Figure 3 is a view like Figure 1 but with the parts in the positions they assume after the apparatus is sprung:

30 Figure 4 is a perspective of the apparatus on a reduced scale.

Figure 5 is a cross-section taken in the plane indicated by the line 5—5 of Figure 1 not showing the casing cover closed.

35 Similar numerals of reference designate corresponding parts in all of the views of the drawings.

Among other elements my novel apparatus comprises a casing body 1 to which is 40 hingedly connected at 2 a cover 3, said cover being adapted to be detachably secured in closed position by hooks 4 or other appropriate means. At the top of the cover 3 are provided longitudinal ribs 5 and 6,

45 the ribs 6 being comparatively short and being arranged at opposite sides of an opening 7 in the cover and through which is adapted to be dropped a heavy ball 8 of steel or any other appropriate material.

50 Manifestly when a blindfolded candidate for initiation manipulates the ball 8 between the ribs 6 until the ball is coincident with the opening 7, the ball will drop through the opening into the casing.

Within the casing body are two compressible bulbs 9 adapted to be charged with water or any other appropriate fluid. The said bulbs 9 are provided with nozzles 10 which extend through and are carried by the cover 3. From this it follows that when the cover is open the bulbs 9 will be lifted out of the casing body 1, and it also follows that through said nozzles 10 the bulbs may be expeditiously and easily charged with liquid. When the cover 3 is closed the said bulbs 9 rest against opposite end walls of the casing body 1, and adjacent to the working position of one of the bulbs 9 is arranged a solid abutment 11 which is fixed to the bottom of the casing body and is preferably formed of steel or other appropriate material. Also fixed to the bottom of the casing body 1 and spaced from the abutment 11 is a holder 12 for blank cartridges 13, Figures 2 and 5. In this connection I would have it understood that the abutment 11 is provided opposite the cartridge holder in order to prevent any wads or the like from injuring the apparatus when the cartridges 13 are exploded. It will also be understood that the abutment 11 will tend to preclude injury to bystanders in the event of a loaded cartridge being inadvertently placed in the holder 12 and discharged incident to the operation of my apparatus. 85

Appropriately guided on the bottom of the casing body 1 is a longitudinal central rectilinearly movable plunger 14, said plunger 14 having firing pins 15 at its forward end.

The plunger 14 is provided at 16 with a recess for the engagement of one end of a trigger lever 17 which is fulcrumed at 18 and is adapted when the apparatus is set to have its upper end rest under the aperture 95 7. A retractile spring 19 is interposed between and connected to the plunger 14 and the casing body 1, Figures 1 and 3, and when the apparatus is set as shown in Figures 1 and 2 it will be manifest that the said spring 19 will be tensioned. Therefore, when the lever 17 is rocked by the weight of the ball 8 and the plunger 14 is released and the plunger 14 will be powerfully impelled forwardly with the result that the fire pins 15 will explode the cartridges 13. This manifestly will be calculated to startle the candidates who will hold the apparatus on their

laps and because of their likely consternation will afford great amusement to on-lookers.

In the practical use of my novel apparatus I prefer that the candidates be located in chairs opposite each other with the ends of the casing body on their laps, this in order that jets of water may be thrown in the faces of the candidates co-incident with the exploding of the cartridges 13.

To the end indicated I provide for compression with the bulbs 9 two swinging pressers 20, hinged at 21 to the casing body. These pressers 20 are connected at 22 to appropriately guided cables 23 which, in turn, are connected to the ends of a retractile spring 24, extending longitudinally of the apparatus as best shown in Figures 3 and 4. Manifestly when the pressers 20 are swung inwardly or away from the bulbs 9, the spring 24 will be put under tension, and when the pressers are suddenly released the spring 24 will suddenly contract and crowd the pressers 20 against the bulbs 9 with the result that the latter will be compressed and water will be ejected suddenly therefrom. For the purpose of retaining the pressers in the positions shown in Figure 1 until the plunger 14 is released I provide the mechanism best shown in Figures 1 and 2. This mechanism comprises rods 30 and 31 loosely connected at their outer ends to the pressers 20 and having hooks 31 at their inner ends, and a T-shaped keeper 32 having flanges 33 at the ends of its head for the engagement of the hooks 31 after the manner shown in Figure 2. The stem of the T-shaped keeper 32, which is pivoted at 34, is arranged in the path of a lateral projection 35 on the plunger 14, and consequently it will be understood that when the plunger 14 is released and is manipulated toward the rod from the position shown in Figures 1 and 2, the projections 35 will swing the keeper 32 out of engagement with the rods 30 so as to release the said rods, whereupon the pressers 20 under the action of the spring 24 will suddenly compress the bulbs 9 for the purpose before stated.

I prefer to provide the casing body 1 in one of its side walls with an opening controlled by a hinged door 40 made up of a frame and reticulated material 41 in the frame. The said door 41 will permit of the emission of smoke and sound from the interior of the casing, and will also permit an attendant to reach into the casing for the purpose of adjusting some of the parts when necessary. I do not desire, however, to be understood as confining myself to the said opening and door inasmuch as the same may be altogether omitted without affecting my invention.

It will be apparent from the foregoing that notwithstanding the practical advan-

tages ascribed to my novel apparatus, the apparatus is simple and inexpensive in construction and is well adapted to withstand the usage to which lodge apparatus is ordinarily subjected.

I have specifically described the preferred embodiment of my invention in order to impart an exact understanding of the same. I do not desire, however, to be understood as confining myself to the said construction inasmuch as the scope of my invention is defined by my claims and within the said claims changes or modifications may be made without involving departure from the scope of the invention.

Having described my invention, what I claim and desire to secure by Letters-Patent, is:—

1. In an initiation apparatus, the combination of a casing having an opening in one of its walls, a cartridge holder in the casing, a plunger guided in the casing and provided with a firing pin, a spring for impelling said plunger toward the cartridge holder, a movable keeper detachably engaged with the plunger to prevent movement thereof under the action of the spring and having a free end arranged opposite said opening and a weighted object adapted to be passed through said opening to contact the free end of said keeper for releasing the same.

2. In an initiation apparatus, the combination of a casing having an opening centrally arranged in its top wall, a cartridge holder in the casing, a plunger guided in the casing and provided with a firing pin, a spring for impelling said plunger toward the cartridge holder, a movable keeper detachably engaged with the plunger to prevent movement thereof under the action of the spring and having a portion arranged opposite said opening; the said keeper being in the form of a lever fulcrumed at an intermediate point in its length, and the said plunger being provided with a portion for the engagement of the heel end of said lever, a weighted ball adapted to be passed through said opening to contact said keeper for releasing the same and guiding means for said ball arranged on the top of said casing.

3. An initiation apparatus of the character described comprising a casing including a hinged cover formed with an opening centrally disposed therein, compressible bulbs one arranged at each end of said casing and each having an orifice arranged to discharge exteriorly of the casing and through the hinged cover, swinging pressers adapted to compress said bulbs, cables guided in said casing and each having connection with one of said pressers, a spring for each cable and having the opposite ends thereof fixed in said casing whereby the swinging pressers

are retained in normal position, a swinging T-shaped keeper having upturned flanges arranged thereon, rods having one of their ends connected to the swinging presser and the opposite end detachably engaged with two of said flanges, a spring actuated plunger mounted for sliding movement in said casing, an abutment projecting from said plunger, and a movable keeper having 10 one end detachably engaged with the plunger to normally hold it against move-

ment by said spring last mentioned, and means adapted to strike the opposite end of said keeper for releasing said plunger whereby the abutment thereof will engage 15 the T-shaped keeper for swinging the latter in a horizontal plane so as to release the rods therefrom.

In testimony whereof I affix my signature.

ARTHUR J. HASBROUCK.
